UNITED STATES PATENT OFFICE.

LEON LOBEL, OF NEW YORK, N. Y.

ARCH-SUPPORT.

1,261,042.

Specification of Letters Patent.

Patented Apr. 2, 1918.

Application filed April 30, 1917. Serial No. 165,885.

To all whom it may concern:

Be it known that I, LEON LOBEL, a citizen of the United States of America, residing at New York city, county and State of New 5 York, have invented certain new and useful Improvements in Arch-Supports, of which the following is a full, clear, and exact description.

This invention relates to improvements 10 in arch-supporters, and pertains more particularly to a novel form of base-plate upon which a yieldably supported bridge-piece is mounted. One of the objects of my invention is to provide a base-plate which is 15 flexible at the ends thereof, the whole plate being resilient and sufficiently yieldable so as to conform to the shape of a shoe when weight is placed thereupon; in other words, the base-plate is flat until weight is placed 20 upon it, at which time it will be flexed and conform to the shape of the sole portion of a shoe. The base-plates of arch-supporters now on the market are generally, as far as I am aware, preshaped to fit the inner sole 25 portion of a shoe, and for this reason usually rigid and not flexible.

My improved base-plate is made out of metal, preferably steel, thin yet resilient enough to be flexible to a degree sufficient 30 to permit it to be conformed, by the weight of the wearer, to the shape of the inner sole portion of a shoe, and to be flexed by the movements of the feet, particularly at the ends thereof, during the ambulatory 35 movements in order to permit more natural walking, and at the same time, by the springy reactions of the ends of the base-plate, producing a massaging effect upon the contiguous muscles.

40 Other features and advantages of my improvement will hereinafter appear.

I will now proceed to give a detailed description of my invention in connection with the accompanying drawing, wherein—

45 Figure 1 is a plan view of my improved arch-support, broken away to show the yieldable elements;

Fig. 2 is an enlarged cross sectional view, the section being taken on a line 2—2 in 50 Fig. 1.

Fig. 3 is a fragmentary side view, looking from the left in Fig. 2; and

Fig. 4 is an edge view of another form of base-plate or member.

55 My improved arch-supporter comprises a

base-plate 1, which is normally flat, as shown by full lines Fig. 3, that is to say, flat until weight is placed thereupon, at which time the plate will be flexed, as shown by dotted lines in Fig. 3, to fit the contour 60 of the inner sole portion of a shoe. The plate 1 is made of relatively thin resilient metal, preferably steel, to which is secured, by rivets or the like, a springy-supporting arch or bridge 2, consisting (in this instance) of a plurality of resilient steel tongues or fingers 3. The tongues 3 are shaped to fit the arch of the foot, and are secured to the base-plate at 4 by rivets or the like.

In combination with the arch or bridge, I provide a supplemental cushioning device, in this instance a coil spring 5, which at its lower end rests upon the plate 1, the upper end releasably engaging a lug 6 on a 70 supporting-plate 7 which is secured, as at 9, to certain of the tongues 3. The supporting-plate 7 is preferably in the form of a leaf-spring consisting of the leaves 7^a and 7^b, thus providing a strong and highly resilient support for the tongues 3. The ends 75 10 of the supporting-plate rest upon the base-plate 1. The spring 5 is removably held in position, that is to say, is placed so that it can be removed without the necessity of removing any other element of the 80 supporter. To remove the spring, it is but necessary to compress it to cause the upper end thereof to become disengaged from the lug 6. This feature of the supporter is im- 85 portant, as it sometimes becomes necessary to renew the springs or to insert springs of a greater or lesser tension.

During the ambulatory movements, the 90 ends 11 and 12 of the base-plate 1 will yield and react, thereby lessening the rigidity of the supporter. For example, the forward end 11 of the plate will be at about the ball portion of the sole, that is to say, at the 95 position where the ball of the foot normally rests. During the ambulatory movements, it is this portion of the shoe that flexes most; hence, the end 11 of the base-plate will also flex or bend to a much greater extent than the corresponding end of the base- 100 plates of the ordinary arch-supporters. While the base-plates of such arch-supporters may have a very slight degree of yieldability, they "give" as an entirety, but are not flexibly resilient in the sense and for 105 110

the purpose herein described in connection with my improved device. In other words, the ends of the ordinary base-plates will not bend independently of the remainder of the plates.

For very heavy wearers, I may reinforce the central portion of the plate 1 by a superposed flexible steel-plate 13, which does not extend to the ends thereof.

10 What I claim as my invention is:

1. A steel spring base plate of inherent resiliency, in combination with an arched resilient supporting plate and an interposed spring, the whole constituting an arch sup-

15 porter.

2. A normally horizontal resilient base plate, in combination with an arched resilient supporting plate resting thereon, the ends of said base plate extending beyond 20 said supporting plate and being adapted to bend independently under the pressure of the wearer's foot.

3. In combination with a resilient arched supporting plate, a base plate on which it 25 rests, the ends of which extend beyond said support and are inherently flexible and resilient, and a removable spring interposed

between said base plate and said supporting plate.

4. An arch supporter provided with a 30 base plate, the ends of which extend beyond the remainder of the supporter and are inherently flexible and resilient.

5. In an arch-supporter, a resilient base-plate having its ends projecting beyond the 35 remainder of the arch support and capable of independent movement, a resilient bridge secured thereto, and a resilient supporting-plate therefor consisting of a plurality of resilient superposed leaves, the ends of said 40 supporting-plate resting upon but unsecured to the base-plate, said supporting-plate being secured intermediate its ends to said bridge.

6. In combination with an arch-sup- 45 porter, a metal base-plate the end portions of which are normally flat but flexibly re-

Signed at New York city, N. Y., this 27 day of April, 1917.

LEON LOBEL.
